[57] CLAIM

The ornamental design for a dispensing assembly, as
shown and described.

DESCRIPTION

FIG. 1 is a top, front, and left side perspective view of
a dispensing assembly showing our new design;
FIG. 2 is a bottom, rear, and right side perspective view
thereof;

FIG. 3 is a bottom, rear, and right side perspective view
thereof, shown in an open position with the broken-line
disclosure of a roll being for illustrative purposes only
and forming no part of the claimed design; and,
FIG. 4 is a bottom, rear, and right side perspective view
thereof, shown in an open position.
